Primary Examiner — Mojtaba Tehrani

CLAIM

The ornamental design for a mobile phone case, as shown and described.

DESCRIPTION

FIG. 1 is a perspective view of a mobile phone case showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the mobile phone case where the mobile phone case is in a close state;

FIG. 10 is an enlarge view of portion 10 shown in FIG. 1;

FIG. 11 is an enlarge view of portion 11 shown in FIG. 1; and,

FIG. 12 is an enlarge view of portion 12 shown in FIG. 2. The dash-dot broken lines in FIGS. 1, 2, 10, 11, and 12 disclose the boundary of the enlarged views and form no part of the claimed design.

1 Claim, 12 Drawing Sheets
